In Sweden July 10, 1951

Term of patent 14 years

(Cl. D62—2)

To all whom it may concern:

Be it known that we, Karl Eric Sixten Andersson-Sason and Torsten Brimberg, residing at Stockholm, Sweden, have invented a new, original, and ornamental Design for a Sprayer, of which the following is a specification, reference being had to the accompanying drawing, forming a part thereof.

Fig. 1 is an end elevational view of a sprayer showing our new design;

Fig. 2 is a side elevation thereof;

Fig. 3 is a fragmentary perspective view of the sprayer with the container omitted and the fluid riser conduit broken away for convenience of illustration; and

Fig. 4 is a top plan view of Fig. 3.

The essential features of our design reside in the portions shown in full lines.

We claim:

The ornamental design for a sprayer, as shown and described.

KARL ERIC SIXTEN ANDERSSON-SASON.
TORSTEN BRIMBERG.
